US00D709994S

(12) **United States Design Patent**
King et al.

(10) **Patent No.:** **US D709,994 S**
(45) **Date of Patent:** **** Jul. 29, 2014**

(54) **INSERT PORTION OF A PIPE FITTING**

(75) Inventors: **Thomas A. King**, Chesterfield, MO (US); **Duane K. Smith**, St. Charles, MO (US); **Douglas L. Kirk**, Ballwin, MO (US)

(73) Assignee: **Blazing Products, Inc.**

(**) Term: **14 Years**

(21) Appl. No.: **29/415,421**

(22) Filed: **Mar. 9, 2012**

DESCRIPTION

FIG. 1 is a perspective view of an insert portion of a pipe fitting showing our new design;

FIG. 2 is a top plan view thereof;

FIG. 3 is a bottom plan view thereof;

FIG. 4 is a side elevational view thereof, the opposite side being the mirror image;

FIG. 5 is a front elevational view thereof; and,

FIG. 6 is a rear elevational view thereof.
